FOUNDRY FLASK

James F. Hines, Lakewood, Ohio, assignor to Hazel K. Hines, Lakewood, Ohio

Application December 31, 1938, Serial No. 248,668

4 Claims. (Cl. 22—106)

This invention relates to a foundry flask and is particularly intended for use with modern synthetic molding sands which are generally thrown into the flask by a sand-slinger and pack so hard and firmly as to make removal from a rigid flask difficult, if not impossible. These so-called synthetic sands usually consist of a sharp natural sand mulled dry with talc, which bonds hard when wet but with a glue like quality which makes it very difficult to remove from the flask because it does not slip readily upon the flask sides. Therefore the flask sides have to be separated from the mold by a lateral motion before the mold can be removed.

Sometimes oil is sprayed on patterns or flask walls to overcome this stickiness, but more positive and satisfactory results are obtained by moving the flask walls laterally outward to break the adhesion before the operator starts to lift the flask. Sometimes the sides of the flask are struck with a hammer for such loosening but this obviously is likely to injure the mold, particularly if it has interior hanging parts.

My invention provides a lateral opening arrangement whereby the flask walls can be unlocked and will thereupon separate from the mold sides and break the adhesion. A further purpose of my invention is to give the flask a degree of rigidity and accuracy of size not hitherto obtainable in a separable-wall flask, to insure that the sides will be accurately aligned when again brought together, and to protect against sand interfering with accurate closing or damaging certain guide elements.

The principles of the present invention are applicable to flasks which are generally standard in their characteristics and thus not limited to any specific flask wall construction or specific material. Such flasks may be provided with sand strips, means for holding the flasks in vertical registry when cope and drag are assembled, and other standard fittings.

To the accomplishment of the foregoing and related ends, said invention, then, consists of the means hereinafter fully described and particularly pointed out in the claims.

The annexed drawings and the following description set forth in detail certain structure embodying the invention and method of making the same, such disclosed means constituting, however, only preferred specific embodiments of my invention.

In the accompanying drawings:

Fig. 1 is a perspective of two of my improved flasks assembled but empty;

Fig. 2 is a reduced scale elevation of a corner of one flask only, viewed approximately as indicated by the arrows 2—2 of Fig. 1, and showing the halves separated;

Fig. 3 is a horizontal section on a larger scale showing a corner locking detail and also showing part of the method of construction, the view being downward on plane 3—3 of Fig. 2 with some elements in plan;

Fig. 4 is a horizontal section on plane 4—4 of Fig. 2, with some parts in plan, and taken during construction;

Fig. 5 is an enlarged perspective illustrating the application of certain elements during manufacture;

Fig. 6 is the same section as Fig. 3, but with construction elements removed and flask halves separated;

Fig. 7 is a view corresponding to Fig. 6 but illustrating a modified dowel, and with flask halves closed;

Fig. 8 is a horizontal section through the completed flask on plane 4—4 of Fig. 2, showing the locking means, with halves closed;

Fig. 9 is an enlarged fragmentary vertical section on the plane 9—9 of Fig. 1, with certain elements omitted for simplicity;

Fig. 10 is an elevation of an adjustment lock, the view being indicated by the arrows 10—10 of Fig. 2;

Fig. 11 is a perspective of the opening cams, complementary halves separated for better illustration;

Fig. 12 is a fragmentary sectionalized perspective of an alternative dowel fitting, also showing the manufacturing method; and

Fig. 13 is an elevation illustrating in diagrammatic style the cam positions corresponding to the closed and opened flask respectively.

Referring now to Fig. 1, element 1 is a cope and element 2 a drag, both being snap flasks to which my invention is applied. To dispose of incidental matters it will be mentioned that the cope is equipped with conventional sand strips 5, moved by thumb levers 6, and that the drag is aligned on the cope by conventional pin fasteners 7.

The cope and the drag are each vertically parted at diagonally opposed corners, the parting plane being indicated by reference character 9, Figs. 1 and 2. Dowels 11, Figs. 3 and 6, or 12, Fig. 7, align the halves, while locking bolts 13 keep them together.

The bolts pass freely through holes in the flask corners and also through crown cam elements 14 (not threaded) each secured to the side of a

corner. The cams 14 work against complementary cam-faced nuts 15, with finger holds 16, threaded upon said bolts. The slope of the cam faces is steeper than of the screw threads (no conclusions in this respect are to be drawn from the diagrammatic showing of Fig. 11), so as to give faster axial movement to the bolt 13 when the nut 15 is turned than would be given by the threads alone. The cam faces and the threads 10 are both directed in the same sense, left hand in the cope, right hand in the drag, so that the jolting effect in each instance will cause the weight of the finger holds 16 to tend to keep the corner closed. Thus in the assembled positions 15 of Fig. 1 the holds 16 on the cope must be moved up to open the corner, and those on the drag moved down to open the corner.

The dowels are set into, and the bolts pass through, cast metal filling 25 in corner grooves 20 26 in the flask wall ends; the corners are similar in a general way to those of my Patent No. 2,006,240. The arrangement of these elements will be described in connection with the preferred method of making.

25 The preferred method is to assemble the side walls in closed position on a forming block 30 in the manner illustrated in Fig. 6 of my Patent 2,006,240, with the dowels 11 (or 12) and cores 27 for the bolt holes all set in a parting plate 31, which is preferably edged as at 32 to form the bevelled spacing beads 33. At this stage the dowels are assembled with dowel sleeves 11A and socket bottoms 11B in the parting plate, the corner is clamped on the forming block 30 as by a C-clamp 34 (Fig. 12) or other means, and metal 30 25 poured in, giving the result shown in Figs. 3 and 4. The flask halves are then completely separated, plates 31 and cores 27 removed, and the halves then reassembled with springs 18 in the bolt hole enlargements 35, Fig. 8, tending to 40 separate the flask halves, and bolts 13 in place. The beads 33 always maintain the closing distance and by reason of their edge push sand into the sand escape spacing established by the plate 45 31, so that sand will not impair accuracy of closing. Should adjustment become necessary by reason of wear or other causes it can be made by removing the head stop block 37, Fig. 10, and turning the bolt 13, although the principal purpose of this adjustment is to govern the width of 50 separation.

Usually these flasks are made of aluminum, with a top protective steel strip 40, seen in Figs. 1 and 9. At their junction 9 these strips may 55 also be bevelled, Fig. 9, to prevent lodgement of sand, the effect being the same as of the beads 33. In Fig. 9 the metal filling 25 is omitted for simplicity.

Alternative dowel arrangements are shown in 60 Figs. 7 and 12. In Fig. 7 the dowel 12 has double conical ends with cylindrical mid portion. These dowels are put in with a carrying plate such as 31, but when the flask is in service are never pulled far enough out to expose either conical 65 surface. Thus, whether one or both conical ends come loose is of no significance, and the dowel socket is never exposed for sand to get in.

Another dowel arrangement is shown in Fig. 12. Here two identical continuous strips 49 are used, 70 set into the flask corners 26 by cast metal 25 binding upon holding means, such as anchor studs 51. The strips will obviously be perforated at midlength for the passage of the bolts 13 and springs 18. At suitable intervals each of these 75 strips is apertured and threaded for the reception

of a stud 47 and at corresponding intervals has a larger aperture to receive a stud pin 50, these larger apertures preferably being each surrounded by a bead as shown. It is not essential that the apertures pass through the anchor studs, 5 although doing so gives good holding and guiding capacity. By properly positioning the various apertures and turning opposing strips end for end, a single pattern of strip serves for both sides. Sand relief and accurate spacing are afforded by the beads 52. In making up this assembly no carrying plate is necessary, but a core such as 27 is used. The flask halves are clamped together against the forming block 30 and the metal 25 poured in. After the metal 10 cools it is necessary to separate the flask halves 15 to withdraw the core 27, and insert bolts 13 and springs 18.

In operation the flasks are closed upon the beads 33 or 52, with the high ends 60, 61 of the 20 cams 14 and 15 face to face, as indicated diagrammatically in the upper part of Fig. 13, thus putting bolt 13 in tension and compressing spring 18. Turning the cam 15 allows the spreading tendency which has been imparted to the flask 25 walls by packing the sand therein, together with the force of the spring 18, to separate the flask halves to the position of Fig. 6. In this movement the element 14, which is not threaded, travels further out on the bolt. Thus the flask 30 walls are loosened from the tightly packed sand so that the flask can easily be lifted off the mold without danger of injuring the mold, but the guidance by the dowels prevents any impairment 35 of alignment of the halves, and opposite movement of the cam nut 15 brings the flask halves together again to exactly the original size and relative position. The opening movement need not be great; in practice about one-sixteenth to one-eighth of an inch is usually sufficient. 40

On account of the greater inclination of the cam surfaces than the screw threads, the extent to which the flask halves separate can be regulated for any desired opening distance by turning the head of the bolt 13, which is then locked by 45 the block 37 or otherwise.

It will be seen from the foregoing that I have invented a flask and a method of making the same in which the accuracy of a rigid flask is combined with the advantage that a snap flask 50 has in easier removal from the mold without danger of breaking the sand or pulling any of the sand away with the flask walls. The flask walls can be quickly and easily separated as little or as much as necessary to accomplish this result, 55 usually very little, and are brought back on closing to exact original alignment and dimensions. There can be no misalignment when the flask is again closed, nor does the sand, always present in foundry work, interfere with this result. 60

It will be understood that the scope of the invention is to be measured by the following claims rather than by the description.

I claim:

1. In a separable corner foundry flask, guide means enclosed within the wall thickness of a flask corner, said guide means comprising dowels and closed-end sockets, and said dowels including portions completely closing entrance to said sockets, and stops so related to said dowel portions as to prevent travel of said dowel portions out of said sockets. 65

2. A foundry flask comprising, in combination, walls vertically separated at opposing corners and dowels rigidly set in one element of each such 70 75

corner with corresponding sockets in the other element, said sockets limiting the penetration of said dowels in said other element and being formed by casting molten metal upon said dowels and said dowels and sockets being housed in the flask walls of said corners.

3. A foundry flask comprising, in combination, walls vertically separated at opposing corners, dowels rigidly set in one element of each such corner with corresponding closed sockets in the other element, said sockets being formed by casting molten metal upon said dowels and said dowels and sockets being housed in the flask

walls of said corners, and means for limiting withdrawal of said dowels from their sockets and for closing said flask.

4. A foundry flask comprising, in combination, walls vertically separated at opposing corners and dowels engaging opposing sockets in each of said walls, said sockets limiting the penetration of said dowels in each of said walls and being formed by casting molten metal upon said dowels, said dowels and sockets being housed in the flask walls of said corners.
